UNITED STATES PATENT OFFICE.

ALBIN F. BRAFF AND FRITZ OTTOSON, OF SUPERIOR, WISCONSIN.

DOOR CHECK AND HOLDER.

Application filed May 21, 1924. Serial No. 714,794.

Our invention relates to the art of devices for buffing, checking and holding, spring actuated doors and while especially designed for screen doors it may be adapted for use with any door.

Our object is to produce a device for this purpose which will be strong, durable, simple and of practically inexpensive construction, and which may be easily and quickly assembled and as easily attached for operative use to any door.

Other objects are substantially the same as those of other devices developed in this art which are designed to prevent the door from slamming when returned by the spring to its closed position, to prevent any rebound of the door and hold it tightly closed.

Devices for this purpose are subjected to very severe and strenuous use and experience has shown us they must be constructed to withstand severe shocks. Also repairs are sometimes necessary and to this end we have simplified the construction by forming a heavy carrying frame to which the operative parts are attached without the necessity of rivets.

A clear and complete understanding of our invention will be more easily obtained by reference to the accompanying specification, claims and drawings, in which,

Fig. 1 shows a side elevation view of our device secured in position and holding the door closed;

Fig. 2 shows a side elevation view of our device in open position, the door engaging it to return it to a closed position in which it will hold the door firmly closed;

Fig. 3 shows a plan view of our device;

Fig. 4 shows a longitudinal sectional view of the same; and

Fig. 5 shows a detail view of our carrying frame.

Referring to the accompanying drawing the reference numeral 10 is used to indicate the door and 11 the door casing at the swinging edge of the door. To the door casing we attach a bracket preferably formed of a strip of sheet metal folded to form parallel side walls 13 and 14, the lower ends 15 and 16 being turned outwardly to engage the door casing and provided with orifices 17 and 18, respectively, to receive screws by which the bracket is secured to the door casing. The side walls 13 and 14, are each provided with an orifice, 19 and 20 respectively which are oppositely disposed

and for purposes hereinafter set forth. The central portion of the bracket has a web 12 connecting the two side walls 13 and 14, and an orifice 21 is provided therein.

60

The movable operating part of our device comprises a pair of parallel arms 22 and 23, preferably crescent-shaped in conformation, and spaced from each other, their ends being connected to each other by rivet pins 24 and 25 respectively, and each pin has a roller, 26 and 27 respectively, mounted thereon. Also each arm is provided with two spaced, and preferably registering orifices to receive the carrying frame which will now be described. The carrying frame, designated by the numeral 28, is formed, preferably, of a heavy, strong, and not easily bent, wire, or it may be of spring steel, shaped to form two parallel sides and an end cross piece 34, retaining lugs 29 and 30 extending outwardly from the point of junction, preferably of the parallel sides and cross piece, the ends of this wire forming the frame turning outwardly to form the lugs 80 31 and 32. The carrying frame is of such a size, and so formed, that when the parts of our device are assembled the lugs 29 and 30—also 31 and 32—will engage and extend through their respective orifices of the arms 22 and 23, and the parallel sides of the frame will lie against the inner surfaces of their respective arms, as shown. The lugs 31 and 32 are of sufficient length to also extend through the orifices 19 and 20 respectively, thus pivotally connecting the carrying frame 28, and the arms 22 and 23, to the side walls 13 and 14. A coil spring 33, with a hook at each end, is secured by one of its ends to the cross piece 34 of the frame, as shown its other end passing through the orifice 21, and is thus secured to the web 12.

It will be observed that the relation of the cross piece 34 to the pull of the spring 100 33, and pivotally operating lugs 31 and 32, and the length and conformation of the arms 22 and 23, and the mounting of our device to the door casing, is such that when the door is opened it engages the roller 27 105 forcing the arms outwardly against the compression of the spring 33 until the cross piece 34 has passed its dead center, and at this time the roller 27, travelling on an arc from the pivotal mounting, is out of engagement with the door which may be freely opened. As the roller 27 assumes this outer

110

position, and is held there against the compression of the spring (as the cross piece has passed its dead center in its relation to the pull of the spring) the roller 26 has been moved inwardly to the position shown in Fig. 2, so that it is in the path of the door as it returns to its normal closed position. As the door returns to the closed position it contacts this roller 26 and forces it outwardly and when the cross piece 34 has again crossed its dead center the normal operation of the spring 33 forces the roller 27 against the door and clamps it against the closed door thus holding it in a tightly closed position.

By our construction as thus shown and described, it will be apparent that the strong, heavy, carrying frame provides a rigid and strong mounting for the arms and that this strength adds greatly to the life of our device, for it must be borne in mind that the arms are subjected to hard and strenuous shocks against which they should be protected. Again it will be noted we have provided a device which is easily and quickly assembled by an unskilled mechanic and that the only necessary riveting consists in seating and securing the two rivets 24 and 25.

In the drawings we have illustrated only our preferred form of construction and we do not desire to be limited in the scope of our construction, except as set forth in the appended claims.

Having thus described our invention what we claim and desire to secure by Letters Patent of the United States is:

1. A door check comprising a bracket secured to the door casing, a carrying frame

pivotedly secured to the bracket, a pair of crescent shaped arms rigidly secured to said frame, a spring extending between the bracket and the casing frame, means on said arm to engage the door and hold it in closed position with means when the door is open to hold the closing means in open position and to place a tripping means in the path of the door as it closes, said tripping means releasing the spring actuated frame when it is engaged by the closing of the door which forces the closing means against the door.

40

45

50

2. In a door check comprising a housing containing a pivotally mounted checking and holding means, a rigid carrying frame pivotally secured to the housing and rigidly secured at a multiplicity of points, to the checking and holding means.

55

3. A door check comprising a bracket secured to the door casing, a pair of crescent shaped arms held in spaced relation by rollers mounted intermediate said arms and adjacent their ends, a carrying frame formed of two parallel sides which fit inside of said crescent shaped arms, a connecting cross piece on said frame formed integrally therewith, outwardly extending lugs at one end of the sides of said frame, means on said frame to secure said frame rigidly to said arms there being orifices in said arms through which the said lugs extend and bearings in said bracket in which said lugs are journaled, spring actuated means to cause one of the said rollers to hold the door in closed position.
